UNITED STATES PATENT OFFICE

FRANK LEWIS SORDELETT, OF RICHMOND, VIRGINIA

SHOE STRETCHER

Application filed June 25, 1929. Serial No. 373,554.

This invention relates to shoe stretchers, and more particularly to an inflatable stretcher.

One of the objects of this invention is the provision of an inflatable stretcher for enlarging a shoe.

Another object of this invention is the provision of an inflatable stretcher adapted to operate in either right or left shoe.

10 A still further object of this invention is the provision of last-like member in operative relation with an inflatable member so as to stretch a shoe in various directions.

Other objects and features will more fully appear from the accompanying drawings and following description, in which:

Fig. 1 is a shoe showing the invention therein;

Fig. 2, a longitudinal cross sectional view;

20 Fig. 3, a top plan view;

Fig. 4, a top plan view along lines 4—4 of Fig. 2;

Fig. 5, a cross sectional view along lines 5—5 of Fig. 3;

25 Fig. 6, a modification, partly in section, showing fastening means;

Fig. 7, a longitudinal modification in elevation;

Fig. 8, an end view in elevation;

30 Fig. 9, a modification showing ball and socket air connections;

Fig. 10, a sectional end view in elevation showing ball and socket connections, and

Fig. 11, a detail of said connection.

25 Referring to the drawings, a last or form 1, having a circumferential groove 2, around a medium stock 3, is shaped so as to substantially conform to the size of a shoe.

30 A tube 5, made from any flexible material, such as rubber, is provided with the usual air valve 6, and adapted to engage said groove. The valve 6 projects from the posterior of said last and is inflated by an air pump 7; well known to the art.

40 Fig. 6 is a modification showing a grooved last 8 consisting of an upper section 9 and lower section 10. A spring catch 11 is secured in the lower section and adapted to be disposed in an aperture 12 of said upper section, and engage a lip 13, projecting from said sec-

tion, so as to securely hold the two sections together; or by disengagement of said catch from said last, permit expansion of said sections when the tube is inflated.

Fig. 7 is another modification showing an 55 upper section 14 hinged to a lower section 15 so that when the tube is inflated, expansion of said sections may take place in a direction around the axis of said hinge.

Fig. 9 is a still further modification showing 60 a socket 16 screwed to a threaded valve 17 connected to a tube. A hollow ball 18 engages channel 19 in said socket and the usual ball and socket motion is obtained by the foregoing arrangement. It will be noted 65 that the valve head is secured to lower hinge 20 by a nut 21 and said socket.

By inserting the last into a shoe, in the manner shown in Fig. 1, and inflating the tube, expansion takes place outwardly and 70 the shoe is thus stretched. The friction between said shoe and tube, when the latter is expanded, tends to hold the last in a fixed position and the latter cannot slip toward the heel. The modification shown in Fig. 6 functions in a similar manner to that just described and in addition, when the spring catch is released, the last members may expand along with the tube; while the modification shown in Fig. 7 provides an arrangement whereby expansion may take place 75 around the axis of a hinge which secures the sections together.

By the provision of the ball and socket member shown in Fig. 9 elimination of rubber tube is obtained and the pump can be connected directly to the ball member thereby serving both as inflatable means and a handle.

If too much space is allowed between the 90 posterior sections of the last the tube, when inflated, will escape therefrom; which is an undesirable condition. By the provision of protruding supports on each of the sections, which substantially closes the posterior portions of said last, said tube is thus prevented 95 from escaping.

Having described my invention, I claim:

1. In a device of the character described 100 a last having a substantially semicircular

groove on the periphery thereof, and an inflatable means, adapted to engage said groove, for stretching purposes.

2. In a device of the character described a last consisting of an upper and lower section respectively provided with a stock, a peripheral groove in said last substantially formed by said stocks, and an inflatable means engaging said groove, in operative relation with said sections, for stretching purposes.

3. In a device of the character described a last consisting of upper and lower sections respectively provided with stock portions substantially forming a circular peripheral groove, a tube in said groove, and means for securing said sections.

4. In a device of the character described consisting of a last having an upper and lower section hinged together at the posterior thereof, and an inflatable tube between said sections for stretching purposes.

5. In a device of the character described consisting of a last having an upper and lower section hinged together, a tube between said sections, a valve on said tube, and a ball and socket member engaging said valve for connection with a source of pneumatic supply.

6. In a device of the character described a last comprising upper and lower sections grooved to form a peripheral groove, and an inflatable member adapted to engage said groove for stretching purposes.

In testimony whereof I have hereunto set my name this 15th day of June, 1929.

FRANK LEWIS SORDELETT.
